UNITED STATES PATENT OFFICE.

THOMAS WALKER, OF BERGLAND, MICHIGAN.

SAW-SWAGE.

No. 802,836.

Specification of Letters Patent.

Patented Oct. 24, 1905.

Application filed October 20, 1903. Serial No. 177,776.

To all whom it may concern:

Be it known that I, THOMAS WALKER, a citizen of the United States, residing at Bergland, in the county of Ontonagon and State 5 of Michigan, have invented a new and useful Saw-Swage, of which the following is a specification.

My invention relates to saw-swages, and is an improvement on the saw-swage for o which I was granted United States Letters Patent No. 608,494.

The objects of these improvements are to provide means for taking up wear on the eccentric; to provide suitable adjustable stops, 5 so that the action of the eccentric on the saw-tooth can be regulated; to provide an improved construction of the anvil, and to allow a wider range of adjustment in the saddle.

My invention consists in the novel features o of construction and combination of parts hereinafter described, particularly pointed out in the claim, and shown in the accompanying drawings, in which—

Figure 1 is a perspective view of my device 5 complete. Fig. 2 is a side elevation showing the side opposite to that shown in Fig. 1. Fig. 3 is a transverse vertical section through the swage-block. Fig. 4 is a section through the swage-block at right angles to that shown o in Fig. 3, the eccentric being shown in elevation. Fig. 5 is a perspective view of the anvil-carrying block. Fig. 6 is a perspective view of the anvil. Fig. 7 is a perspective view of the eccentric-shaft.

In the drawings, A represents the swage-block substantially cylindrical in form. The lower half of this block is diametrically slotted, as at A'. An axial bore A² extends from one face of the block to the slot A'.

The top of the block is cut off, leaving a smooth flat upper surface, and extending downward from the central portion of this surface is a recess or opening A³, communicating at its lower end with the slot A'.

Through the lower slotted portion of the block, slightly below and to one side of the bore A², is a bore A⁴, intersecting the slot, and on each side of the latter a bushing B is fitted into the bore A⁴. The inner ends of

o these bushings extend into the recess A³ at its lowermost corner, and the bushings are notched, as shown in dotted lines in Fig. 4. Fitting in these bushings and rotating therein is a shaft C, having intermediate its ends 5 an eccentric portion C' and adjacent one end a plurality of annular grooves C². Ad-

jacent the other end the shaft is polygonal and tapering, as shown at C³. On this portion is tightly fitted a ratchet C⁴. This latter has the teeth formed on the outer side 60 of an inner flange C⁵, and on the smooth cylindrical portion adjacent the teeth fits a handle C⁶, having ratchet-teeth C⁷ co-acting with those carried by the flange C⁵. This shaft C slides and rotates in the bushings B, the eccentric portion working in the slot and lower portion of the recess A³. On each side of the recess A³ is formed a parallel threaded socket. A plate D is provided with a depending sleeve D', which extends 65 downward into the recess A³ when the plate is in position on the cut-off portion of the swage-block, the bore of the sleeve extending or being continued upwardly through the block and threaded in its upper portion. At 70 each end of the plate is arranged a depending flange D², which fits over the sides of the block and holds the plate from endwise movement. An elongated transverse slot D³ is formed in the plate on each side of the sleeve 75 and is adapted to register with one of the threaded sockets formed parallel to the recess A³. The plate is adjustably held to the block by threaded bolts and washers, the bolts D⁴ passing through the slots D³ and fitting in the sockets. The lower portion of the sleeve is cut away on the side adjacent the eccentric. An anvil E is adjustably held in this cut-off portion of the sleeve and has a stem E' extending upwardly in the sleeve. 80 The under surface of the anvil is slightly beveled downwardly and rearwardly from the eccentric, as shown at E². A threaded rod E³ works in the upper portion of the sleeve, which is also threaded, and bears on the upper end of the stem E', limiting upward movement of the anvil. The rod E³ has a polygonal head E⁴ at its upper end adapted to be turned by a wrench. The sleeve D' has a limited amount of play in the recess A³ and is adjusted and held in the desired position by the threaded bolts F working through suitable threaded bores in the swage-block, the inner ends of these bolts bearing on opposite sides of the sleeve. 90

To limit the movement of the handle C⁶ in one direction and the consequent throw of the eccentric C' toward the anvil, an adjustable stop is provided as follows: To that side of the swage-block on which the handle C⁶ is located a bracket G is bolted, the bracket 95 extending slightly to the rear of the block 100

and having a curved slot G' in its rear portion, the curvature of the slot being upwardly and forwardly. An arm G^2 carries at one end a set-screw G^3 , working in the slot G' , by which the arm is secured to the bracket at any point along the slot and at any desired angle to the bracket. At its outer end the arm carries a pin G^4 , extending into the path of the handle C^6 and limiting rearward movement of the handle. On the opposite side of the swage-block is bolted a horizontal forwardly-extending bracket H , having a curved upwardly and forwardly and longitudinally slotted portion or arm H' . To the outer end of this bracket is pivoted intermediate its ends an arm H^2 , longitudinally slotted at H^3 in its forward portion. The arm H^2 has adjacent its rear end a pin extending through the slot of the arm H' , and a suitable bolt and washer H^4 fit on this pin and clamp the arm H^2 at the desired angle, the construction being similar to that shown at G^2 . The saddle comprises a pin J , sliding in the slot H^3 and having a head J' bearing against one side of the arm H^2 , and a nut J^2 , threaded on the pin J , bears on the opposite side of the arm H^2 and clamps the pin against movement along the slot. The pin-head J' has a perforation in which slides vertically a threaded stem J^3 , on which a suitable binding-nut works. At its lower end the stem carries a shoe J^4 , having depending side arms adapted to fit over a saw-blade. A flat wear-plate J^5 is carried by the under surface of the shoe and is adapted, by reason of its length, to be simultaneously on two or more saw-teeth.

The operation of my device is as follows: The saw to be swaged is fitted within the slot A' , the tooth to be acted on having its point brought into position between the anvil and eccentric, the saddle having been adjusted to the desired angle. The toothed edge of the

saw being brought to bear on the wear-plate of the saddle, the saw is clamped in the position by the bolts K , working in threaded apertures K' in the swage-block and extending to the slot A' . One of these bolts may be retained in a fixed position and the other operated by means of a ratchet K^2 and ratchet-handle K^3 , similar in construction to the handle C^6 and its coöperating parts. The saw being clamped in position, the anvil having been adjusted as desired, the handle C^6 is thrown rearward, forcing the eccentric against the tooth in advance of and below the point and crowding the back and crown of the tooth between the eccentric and beveled face of the anvil. This operation is repeated for each tooth to be acted on with the exception of the adjustment of the saddle, which would remain the same for each tooth of the saw.

A pivoted recessed pawl L is adapted to drop into the annular grooves C^2 and lock the shaft C against sliding movement.

Having thus fully described my invention, what I claim as new, and desire to secure by Letters Patent, is—

The combination with a swage-block, an anvil carried thereby, means for setting a saw-tooth on said anvil, a bracket carried by the swage-block and having a curved slot therein, an arm pivoted intermediate its ends to the bracket, a pin carried by the arm and adapted to engage the curved slot of the bracket, said pin being arranged to the rear of the pivotal point of the arm, a nut working on the pin and adapted to clamp the arm to the bracket, and a saddle adjustably carried by the arm.

THOMAS WALKER.
